Des. 212,892
Patented Dec. 10, 1968

212,892

TOY RADIO

Ralph W. Crawford, East Aurora, N.Y., assignor to
Fisher-Price Toys, Inc., East Aurora, N.Y., a cor-
poration of New York

Filed Feb. 28, 1967, Ser. No. 5,995

Term of patent 14 years

(Cl. D34—15)

FIG. 4.

FIG. 1.

FIG. 3.

FIG. 2.

FIG. 1 is a front elevational view of a toy radio showing my new design;
 FIG. 2 is a top plan view thereof;
 FIG. 3 is side elevation thereof, and
 FIG. 4 is a bottom plan view.

I claim:
 The ornamental design for a toy radio, substantially as shown.
